G. C. FORD

DOLL

Filed Oct. 14, 1926

INVENTOR

GLADYS C. FORD.

Richard D. Owen
ATTORNEY.

UNITED STATES PATENT OFFICE.

GLADYS C. FORD, OF BROOKLYN, NEW YORK.

DOLL.

Application filed October 14, 1926. Serial No. 141,614.

This invention relates to dolls or stuffed toys and particularly to the kind having washable covers.

A particular object of the invention is to provide a stuffed doll or other form with a suitable inner stuffed form and an outer cover, the latter of which may be removed from the form so that it can be washed when desired.

10 A still further object of the invention is to provide a stuffed form which, in itself, may be shaped to the configuration of a doll and which will also be decorated or painted to represent a doll's face and body.

15 A still further object of the invention is to provide means for attaching over the stuffed form, a cover, the artistic features of which can be made to represent an animal or a human, means being provided for attaching the cover in place, the attaching means being carried by the stuffed form rather than on the cover portion.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in front elevation of my complete doll or toy showing the cover broken away to disclose the interior stuffed form, the cover being shown to conform to the contour of the inner stuffed form.

Figure 2 is a rear view in elevation of the figure or doll, illustrated in Figure 1, showing how the cover may be secured at its back to the stuffed form.

Figure 3 is a view in elevation showing the rear of the stuffed form upon which are provided buttons to which the cover may be secured.

45 Figure 4 is a view in elevation of one form of cover showing the construction thereof and being broken away to show the construction of the rear portion thereof wherein a button holding strip is provided, and

Figure 5 is a section taken on the line 5—5 of Figure 3 showing the method of forming the stuffed insert of the doll and also of attaching the buttons thereto.

55 Referring to the drawings in detail, 5 indicates a stuffed form which may be made in

the configuration simulating a doll, and comprising a head portion 6, body portion 7, leg portions 8 and feet portions 9, the body, leg and feet portions being of an outline whereby 60 the arms, or if desired, the legs may be printed directly upon the covering of the stuffed form, which is held in shape through the medium of suitable interior stuffing or wadding 10, the form being sewn interiorly 65 as at 11 in the usual manner and closed at the edge after the form is stuffed, as is the usual manner in making up stuffed dolls.

The cover for the stuffed form may be of oilcloth, cloth or any other suitable fabric 70 or waterproof material and may be printed on the front and rear faces with a simulation of a doll or animal figure, as desired, it being of course preferable to represent a doll and allowing for the change by substituting or 75 covering the stuffed form with other printed covers, to be hereinafter referred to. The stuffed form 5, as preferably covered with oilcloth, may be washed without erasing the printed features thereon and in order to 80 change the appearance of the doll, I provide a plurality of covers, one only of which I have illustrated in Figures 1 and 2, consisting of a hollow, fabric member 12, conforming in shape to the contour of the stuffed form 85 5, and comprising the head portion, body portion and leg portion, as hereinbefore referred to.

In order to place the stuffed form within the cover 12, I provide in the back of the latter, a binding or reinforced strip 13, in which is provided the overlapping button holes 14 at both ends thereof. It is evident that this opening can be made large enough to insert therethrough the stuffed form 5 and 95 to close the cover thereover.

It has been a great problem in the laundering of these covers 12, which are printed to represent various animals and different types of dolls, to carry out the washing or cleansing 100 of the covers without breaking the buttons which must necessarily be provided in connection therewith so that the same can be fastened about the inner stuffed form. In order to overcome this objection, I have provided on the back of the stuffed form, the buttons 15 which are sewn directly, as shown in Figure 5, to the stuffed form cover so that when the printed cover or envelope made in configuration similar to the stuffed form but 105 having printed thereon a different type of doll or animal, the same may be fixed to the

stuffed form my buttoning the buttonholes 14 over the buttons 15, bringing the opposite portions of the binding or reinforce strip in superposed relation, thereby preventing the 5 tearing out of a single buttonhole which has heretofore been the case in covers, one side of the opening of which bore the buttons and the other side being provided with the buttonholes.

10 In my particular illustration, I have shown the representation of a cat on the cover 12 but it is to be distinctly understood that I am not limited to the showing of an animal or a human figure, as many variations in the 15 design may be made within the scope of the claim.

It is also evident that the configuration of the doll may be varied without departing from the scope of the invention, the essential 20 feature being the placing of the buttons upon the covering of the stuffed form rather than on the printed cover, which envelops the form. This improvement provides for the 25 washing of a plurality of printed covers without the necessity of supplying each of the covers with buttons, thereby reducing the cost of production of the article by saving material and also by lessening the labor necessary in completing the manufacture of the 30 finished product.

A still further advantage gained by my invention is the possibility of washing a plurality of covers and ironing the same through

a common mangle without danger of breaking buttons, which has heretofore been the 35 case, due to the fact that the buttons have been carried upon the printed cover and when the same is washed, the buttons become broken and are unfit for further use, and must necessarily be replaced before the article can 40 be used in conjunction with the stuffed form.

While I have illustrated and described my invention with some degree of particularity, I realize that in practice various alterations 45 therein may be made. I therefore reserve the right and privilege of changing the form of the details of construction or otherwise altering the arrangement of the correlated parts without departing from the spirit of the invention or the scope of the appended claim. 50

Having thus described my invention, what I claim as new and desire to secure by United States Letters Patent is:—

A doll combination comprising a stuffed form having attaching buttons mounted on its 55 rear surface, a cover for the form having a rear side opening through which the form is passed to position within the cover and said cover being further provided with a companion set of buttonholes adjacent said opening and positioned to have overlapping relation to receive therethrough the buttons of 60 said form.

In testimony whereof I affix my signature.

GLADYS C. FORD.
